UNITED STATES PATENT OFFICE

171,325

FENCE

Bernard Yellin, Chicago, Ill., assignor to Bernard Edward Co., Chicago, Ill., a corporation of Illinois

Application June 29, 1953, Serial No. 25,719

Term of patent 14 years

(Cl. D28—1)

To all whom it may concern:

Be it known that I, Bernard Yellin, a citizen of the United States and a resident of the city of Chicago, county of Cook, State of Illinois, have invented a new, original, and ornamental Design for Fence, of which the following is a specification, reference being had to the accompanying drawing forming a part thereof in which:

The dominant features of my design reside in the portions shown in full lines.

I claim:

The ornamental design for a fence, as shown and described.

BERNARD YELLIN.
